UNITED STATES PATENT OFFICE.

JOHN BROWN HARRIS, OF NASHVILLE, TENNESSEE.

SMOKE-CONSUMING FURNACE.

SPECIFICATION forming part of Letters Patent No. 721,698, dated March 3, 1903.

Application filed April 2, 1902. Serial No. 101,069. (No model.)

To all whom it may concern:

Be it known that I, JOHN BROWN HARRIS, a citizen of the United States, and a resident of Nashville, in the county of Davidson 5 and State of Tennessee, have invented a new and Improved Smoke-Consuming Furnace, of which the following is a full, clear, and exact description.

The invention relates to furnaces for use 10 on boilers, stoves, open fire-grates, kitchen stoves and ranges, and the like; and its object is to provide a new and improved smoke-consumming furnace which is simple and durable in construction, very effective in operation, 15 and arranged to utilize the units of heat contained in the fuel to the fullest advantage to insure complete combustion.

The invention consists of novel features and parts and combinations of the same, as 20 will be more fully described hereinafter and then pointed out in the claims.

A practical embodiment of the invention is represented in the accompanying drawings, forming a part of this specification, in which 25 similar characters of reference indicate corresponding parts in all the views.

Figure 1 is a sectional side elevation of the improvement as applied to a stove. Fig. 2 is an enlarged sectional plan view of the same 30 on the line 2 2 of Fig. 1. Fig. 3 is an enlarged sectional side elevation of the filling-chute, parts being in a different position. Fig. 4 is a front elevation of the improvement as applied to an open fire-grate, parts being broken 35 out. Fig. 5 is a transverse section of the same on the line 5 5 of Fig. 4. Fig. 6 is a longitudinal sectional elevation of the improvement as applied to a boiler. Fig. 7 is a sectional plan view of the same on the line 40 7 7 of Fig. 6, and Fig. 8 is a transverse section of the same on the line 8 8 of Fig. 6.

The stove or heater illustrated in Figs. 1, 2, and 3 consists, essentially, of a fire-box A, preferably made in the form of an inverted frustum of a cone, opening at its apex end into the ash-pit B, the top plate A' of the said fire-box being provided with a central opening A², leading into the combustion-chamber C, having an opening C' in its crown 45 to conduct the heat arising from the burning fuel in the fire-box A into a shell D, concentrically surrounding the combustion-chamber

C and connected at its lower end with the chimney-flue E, the upper end of the said shell having a damper connection F with the 55 said chimney-flue E to produce a direct draft in the combustion-chamber on starting the fire in the fire-box A. The damper connection F is closed after the fire is started in the fire-box.

In the fire-clay wall of the fire-box A is arranged a hot-air-supply pipe G, preferably in the form of a coil and having its lower end G' extending to the outside of the heater, the outer end being preferably provided with a 65 valve H to open the pipe end G' to the atmosphere or to close the said pipe end whenever desired. The inner end of the supply-pipe G opens into an annular chamber I, formed in the top plate A' of the fire-box A, 70 and the said annular chamber I is connected by inwardly-extending radial branch pipes J with the lower ends of vertically-disposed perforated pipes K, arranged in a circle and somewhat spaced apart, as plainly indicated 75 in Fig. 2, the perforations in the tubes K extending on the lateral faces thereof, so as to cause the hot air to pass into the path of the smoke and gases arising from the fire-box A through the central opening A², as indicated by the arrows in Fig. 2. The perforated tubes K support at their upper ends a deflector-plate L to cause the heat to spread in the lower portion of the combustion-chamber C before passing to the crown outlet-opening C'. The fuel is introduced into the fire-box A through a chute N, extending in an inclined direction from the top plate A' through the lower portion of the combustion-chamber C and shell D, the outer end of the 80 said chute being normally closed by a cap O in the shape of a scoop and hinged at O' to the bottom of the chute, at the upper end thereof. The cap O is connected by a link P with a gate Q, hung at its upper end at Q' in the chute N, so as to close the latter at the time the cap O is open, and when the cap is swung into a closed position the link P swings the gate Q open, as indicated in Fig. 1. Now in order to charge the fire-box with fuel the latter is placed into the open cap O, (see Fig. 3,) and then the cap is swung into a closed position, as shown in Fig. 1, so that the fuel slides down the chute N into the fire-box 85 90 95 100

without any danger of cold atmospheric air passing into the fire-box during the introduction of the charge into the fire-box.

In starting the fire in the fire-box the valve 5 H is closed and the damper F is opened, and after the fuel is burning in the fire-box the damper F is closed and the valve H is opened, so that atmospheric air passing through the pipe G becomes heated, as the pipe is heated 10 from the burning fuel in the fire-box heating the wall thereof. The heated air from the pipe G passes into the annular chamber I and through the branch pipes J, so as to be heated to a still higher degree, the highly-heated air finally passing through the perforations in the tubes K to the smoke and gases arising through the opening A², so that a complete combustion of the smoke and gases takes place in the combustion-chamber 15 C by the introduction of the highly-heated air. The heat now passes through the crown-opening C' into the shell D and down the latter around the outside of the combustion-chamber C, to finally pass into the chimney-flue E.

From the foregoing it is evident that the air is highly heated in its passage through the pipe G, annular chamber I, and branch pipes J, so that the hot air readily produces complete combustion of the rising smoke and gases to insure full utilization of all the units 25 of heat contained in the fuel in the fire-box A.

In the modified form shown in Figs. 4 and 35 5 the hot-air-supply pipe G² is arranged in the wall R of the open grate having the fire-box A³, the ash-pit B', and the combustion-chamber C², leading at its upper end into the chimney-flue E'. The lower end of the pipe G² has an outward extension G³, containing a valve H', and the upper end of the pipe G² 40 opens into a chamber I', arranged in the wall R, and from the said chamber I extend the perforated tubes K' in a transverse direction and within the upper end of the combustion-chamber C², so that the heated air passing out 45 of the perforated tubes K' comes directly in contact with the smoke and gases rising in the fire-box and combustion-chamber C², so that complete combustion of the smoke and gases takes place by the introduction of the 50 hot air.

In the modified form shown in Figs. 6, 7, and 8 the hot-air-supply pipe G⁴ is arranged in the brickwork S, supporting the boiler T, one end G⁵ of the pipe opening to the atmosphere and the other end opening into a chamber I² in the form of a coil of pipe, arranged in the top of the bridge-wall, located in the rear of the fire-box A⁴, as plainly indicated in Fig. 6. From the chamber I² extend the perforated tubes K², so that the heated air issuing through the perforations in the tubes K² comes in direct contact with the smoke and gases passing over the bridge-wall through the combustion-chamber C³, to finally pass 60 65 through the boiler-flues, the heat in passing through the combustion-chamber C³ heating the pipe G⁴, so that the air is highly heated

at the time it leaves the tubes K². As indicated in Fig. 6, the pipe G⁴ is arranged in the shape of a coil, forming part of the bottom 70 and rear of the combustion-chamber. In all cases it is understood, however, that atmospheric air is heated and is charged into the smoke and gases arising from the burning fuel in the fire-box to cause complete consumption of the smoke and gases and produce a high heat.

Having thus described my invention, I claim as new and desire to secure by Letters Patent—

1. A smoke-consuming furnace, comprising a fire-box, a coiled hot-air pipe arranged in a wall of the furnace and heated by the burning fuel in the fire-box, said pipe opening at one end into the open air, an air-chamber arranged in a wall of the furnace and into which the other end of the hot-air pipe opens, said chamber having oppositely-arranged and spaced portions forming an opening between said portions at right angles to the passage of 85 the chamber, and oppositely-arranged and perforated pipes projecting from the said portions of the chamber, as set forth.

2. A smoke-consuming furnace, comprising a fire-box, a combustion-chamber, an air-pipe in the wall of the fire-box, opening at one end into the open air, an annular chamber between the fire-box and the combustion-chamber, into which opens the other end of the said air-pipe, and perforated tubes rising in 95 the combustion-chamber and connected with the said annular chamber, as set forth.

3. A smoke-consuming furnace, comprising a fire-box, a combustion-chamber, an air-pipe in the wall of the fire-box, opening at one 105 end into the open air, an annular chamber between the fire-box and the combustion-chamber, into which opens the other end of the said air-pipe, perforated tubes rising in the combustion-chamber and connected with the 110 said annular chamber by branch pipes, and a deflector-plate on the top of the said tubes, as set forth.

4. A smoke-consuming furnace, comprising a fire-box, a combustion-chamber connected with the fire-box by a central opening in the top plate of the fire-box, a hot-air pipe in the wall of the fire-box, opening at one end into the open air and at its other end into an annular chamber formed in the said top plate, and perforated tubes concentric to the 115 said central opening, connected by branch pipes with the said annular chamber, as set forth.

5. A smoke-consuming furnace, comprising a fire-box, a combustion-chamber connected with the fire-box by a central opening in the top plate of the fire-box, a hot-air pipe in the wall of the fire-box, opening at one end into the open air and at its other end into an 120 annular chamber formed in the said top plate, and perforated tubes concentric to the said central opening, connected by branch pipes with the said annular chamber, the said branch 125 130

pipes extending in the said top plate, as set forth.

6. A smoke-consuming furnace, comprising a combustion-chamber, a fire-box, in the form of an inverted frustum of a cone and provided with a top plate having a central opening leading to the combustion-chamber, an annular chamber, and radial pipes extending inwardly from the said chamber, a plurality of perforated tubes projecting into the combustion-chamber and arranged around the central opening of the top plate of the fire-box, the lower ends of the tubes being connected with the radial pipes, a deflector-plate on the upper end of the perforated tubes, and a pipe coiled in the wall of the fire-box and having one end connected with the said annular chamber and its other end opening into the open air, as set forth.
- 20 7. A smoke-consuming furnace, comprising a fire-box having a coiled pipe arranged in its wall, and provided with a top plate having a central opening, an annular chamber with which the other end of the coiled pipe is connected, and branch pipes leading inwardly from the annular chamber, a combustion-

chamber above the fire-box and having an opening in its crown, a plurality of perforated tubes having their lower ends connected with the radial pipes, the said tubes being arranged 30 in the combustion-chamber around the central opening of the top plate of the fire-box, a deflector-plate on the upper ends of the said tubes, and a shell surrounding the combustion-chamber, and connected with the chimney-flue, as set forth.

8. A smoke-consuming furnace, provided with a fire-box, and a filling-chute for the same, having a hinged gate and a hinged fuel-receiving scoop-shaped cap, the gate and cap 40 being connected with each other and arranged to close the gate on swinging the cap open, and to open the gate on closing the cap, to dump the contents thereof into the chute, as set forth.

In testimony whereof I have signed my name to this specification in the presence of two subscribing witnesses.

JOHN BROWN HARRIS.
